CLAIM

The ornamental design for a robot joint having an input flange, an output flange, and a top lid, as shown and described.

DESCRIPTION

FIG. 1 is a first perspective view of a robot joint having an input flange, an output flange, and a top lid.

FIG. 2 is a plan view of a front of the robot joint.

FIG. 3 is a plan view of a back of the robot joint.

FIG. 4 is a plan view of a top of the robot joint.

FIG. 5 is a plan view of a bottom of the robot joint.

FIG. 6 is a plan view of a left side of the robot joint; and,

FIG. 7 is a second perspective view of the robot joint.

The broken or dotted lines in the figures depict portions of the robot joint having an input flange, an output flange, and a top lid only and form no part of the claimed design.
